UNITED STATES PATENT OFFICE

JAMES L. BALDWIN, OF CHICAGO, ILLINOIS

PARCEL CARRIER

Application filed January 27, 1931. Serial No. 511,637.

My invention relates to parcel carriers using an overhead wire track, and is an improvement over my Patent #1,165,565, dated Dec. 28, 1915, my present object being to provide a carrier which automatically releases the parcel for discharge when it reaches its destination.

A further object of the invention is to design the novel carrier with an inclined floor and a discharge gate forward thereof, whereby the parcel may at all times bear against the gate for immediate discharge when the latter is released.

A still further object of the invention is to provide a system of carrier lines with sending stations at various points, the lines converging toward a single zone of destination, whereby parcels from different points may all be discharged into a corresponding number of receptacles at such zone.

With the above objects in view and any others that may suggest themselves from the specification and claims to follow, a better understanding of the invention may be had by reference to the accompanying drawings, in which—

Fig. 1 is an elevation of the novel parcel carrier in the zone of its sending station, and also showing a receiving station equipped for a multiple system of lines of the type referred to;

Fig. 2 is a section on the line 2—2 of Fig. 1; and

Fig. 3 is an enlarged fragment of a vital element shown in Fig. 1.

While the novel carrier is applicable to many situations where a direct sending line is desired, I have designed it more particularly for use in laundries. Owing to the necessity of carrying the identity of a batch or bundle of laundry throughout its course, it is preferable that such batch or bundle be constituted as a parcel with the contents carried in a cloth bag to which an identifying tag is secured. Parcels of this kind may be sent from various sources in the laundry to a common point, such as for the ironing of the contents, and this I accomplish by running lines from the sending points to the ironing zone or other department of the

laundry, thus eliminating the necessity of trips by the help across the floor to collect parcels from time to time for the ironing department.

In carrying out the invention, I provide a simple tray 10 in which the parcel 11 is deposited, the tray being suspended from a carrier 12. The latter is designed along the lines illustrated in Fig. 1 of my patent referred to, and has applied to its base a rugged frame 13 to which is rigidly secured the tray, the latter being fully accessible from the sides. The carrier base further receives a bracket 14, the latter and the frame being secured to the base by a bolt 15; the bracket is further secured to the base at 16.

The bracket 14 has pivoted to it at 14a a depending arm 16a to which a transverse plate 17 is secured, the latter serving as the gate for the tray 10 by depending into the forward end thereof. The tray 10 is inclined, as shown, and its inner surface is polished, so that the parcel 11 slides by gravity to the forward end of the tray, being barred from further motion by the gate 17.

In the head 14b of the bracket 14 is horizontally slidable a square rod 18 which carries a downwardly directed detent 19. On the rear side of the head 14b the rod carries a light spring 20, while in front it carries a shorter and stiffer spring 21; and the forward end of the rod has a rubber head 18a. The rear part of the bracket also has a guide 14c for the rear portion of the rod. The detent terminates over a roller 22a loosely mounted on a cross pin 22, the latter being carried by an extension 23 of the arm 16a forward of the pivot 14a.

The lower end of the detent 19 is slightly gouged to seat the roller 22a, as clearly shown in Fig. 3, this condition locking the gate 17 in the normal position shown, since the detent prevents the rise of the extension 23 of the gate arm 16a. However, when the carrier is sent out and reaches its destination, the cushion head 18a of the rod 18 strikes a bumper plate 24 carried by a hanger or post 25 at the destination terminal of the wire track 26, causing the rod 18 to recede and carry the detent 19 away from the roller 22a,

compressing the spring 20. The front end of the tray 10 is now over a receptacle 27 carried by the hanger 23, and the pressure of the parcel 11 pushes the gate 17 open, causing the parcel to be discharged and to fall into the receptacle 27. It will be noted that the gate is so suspended as to meet no resistance—after released by the detent 19—when pushed by the parcel, so that I need no mechanism or other expedient to secure the discharge of the parcel than the reaching of the destination by the carrier. The spring 20 and the rod 18 ordinarily cushion the shock of the impact with the bumper plate 24, but when the impact is greater and the rod recedes further, its head meets the stiffer spring 21, which takes up the excess shock. The track wire is more elevated at the destination than at the sending point, whereby to cause the carrier to return of itself.

It will be seen that the novel apparatus described above furnishes a simple and quick method of delivering parcels and procuring the automatic return of the carrier. Also, by the use of the single rod 18, I provide for both the shock absorbing element of the carrier and the gate releasing device therefor. The light spring 20 readily yields to the detent 19 the instant the rod strikes the bumper plate, permitting the parcel to push the gate open. Also, the detent acts as quickly to lock the gate again, when the parcel has dropped out of the tray. The obliquity of the latter assures the maintenance of the parcel in a frontal position at all times, whereby to procure its own discharge when the carrier meets the destination. It is therefore seen that the apparatus of the tray and its control is a simple and efficient appendage for the carrier, and fully serves the purposes for which it is intended.

I claim:—

1. A parcel delivery apparatus comprising a carrier disposed for travel along a track from a point of origin to one of destination, a parcel tray suspended from the carrier and having its bottom inclined in the direction of the destination, a barrier for the tray contents at the forward end of the tray, a lock normally effective on the barrier, a bumper element at the point of destination, and a resilient impact element projected frontally from the carrier, said impact element releasing the barrier when meeting said bumper element.

2. A parcel delivery apparatus comprising a carrier disposed for travel along a track from a point of origin to one of destination, a parcel tray suspended from the carrier and adapted to discharge at one end, a pivoted closure for the latter, an extension of the closure beyond the pivot, a rod suspended from the carrier and adapted to recede when the latter reaches the destination, and a detent carried by the rod and normally locking

said extension to prevent the opening of the closure, the recession of the rod releasing the extension.

3. The structure of claim 2, said extension being substantially horizontal, and said detent depending in a substantially vertical course to abut the extension with its lower end.

4. The structure of claim 2, said extension being substantially horizontal, and a roller carried by the extension in the region of its outer end, said detent depending in a substantially vertical course and having its lower end gouged to seat the roller.

5. A parcel delivery apparatus comprising a carrier disposed for travel along a track from a point of origin to one of destination, a bracket attached to the carrier, a rod slideable in the bracket in the course of travel, a frontal projection of the rod serving as an impact element with a bumper at the point of destination, a parcel tray suspended from the carrier, a closure for said tray, and a detent normally locking said closure and releasing the same when the impact occurs.

6. The structure of claim 5, bearings carried by said bracket for the rod and spaced longitudinally thereof, and said detent being carried by the rod back of the frontal bearing.

7. The structure of claim 5, said frontal projection having a cushion head, and a spring to normally maintain the projection in forward position.

8. The structure of claim 5, bearings carried by said bracket for the rod and spaced longitudinally thereof, said detent being carried by the rod back of the frontal bearing, and a compression spring carried by the rod between the detent and the bearing next to the rear thereof and adapted to restore the detent to closure-locking position after the impact has occurred.

9. The structure of claim 5, bearings carried by said bracket for the rod and spaced longitudinally thereof, said detent being carried by the rod back of the frontal bearing, a compression spring carried by the rod between the detent and the bearing next to the rear thereof and adapted to restore the detent to closure-locking position after the impact has occurred, and a spring carried by the rod forward of the frontal bearing, this spring having a greater compression resistance.

In testimony whereof I affix my signature.
JAMES L. BALDWIN.
